UNITED STATES PATENT OFFICE.

FREDERICK L. McCULLOCH, OF TAMPA, FLORIDA, ASSIGNOR TO WATSON ELISAPH DORCHESTER, OF TAMPA, FLORIDA.

CARBURETER ATTACHMENT.

1,262,220.

Specification of Letters Patent. Patented Apr. 9, 1918.

Application filed February 1, 1917. Serial No. 145,968.

To all whom it may concern:

Be it known that I, FREDERICK L. McCULLOCH, a citizen of the United States, residing at Tampa, in the county of Hillsboro and State of Florida, have invented certain new and useful Improvements in Carbureter Attachments; and I do hereby declare the following to be a full, clear, and exact description of the invention, such as will enable others skilled in the art to which it appertains to make and use the same.

The present invention relates generally to carbureter attachments, and more specifically consists in a carbureter attachment with certain additions and improvements over what is shown in my similarly entitled co-pending application Serial No. 125,989, filed October 16, 1916.

One of the objects of my present improvement is to provide an air supply device in connection with the float chamber of the carbureter in order that atmospheric air, or other medium, may be introduced thereto when the speed of the engine attains such a high degree as to create an abnormal vacuum such as has been found to interfere with the proper functioning of the float valve and aspirating nozzle of the carbureter.

Among other objects of the present improvement which will readily suggest themselves to those skilled in this art, may be more particularly mentioned the improved rearrangement of the several parts, more specifically the suction pipe between the float chamber and air intake of the carbureter and improved automatic valve means for simultaneously admitting air to the aspirating chamber of the carbureter, and, when a predetermined speed has been attained by the engine, through a separate connection to the float chamber to relieve the abnormal vacuum which such excessive speed would tend to create, and in this manner preserve substantially a constant degree of vacuum in the float chamber for which the float device may be initially designed and fitted to properly operate and function.

In the accompanying drawings forming a part of this application, and in which simi-

lar reference symbols indicate corresponding parts in the several views:

Figure 1 is a side elevation of an automobile with a portion broken away to illustrate the carbureter with my improved attachment applied thereto.

Fig. 2 is an enlarged elevational view, partly in section, of a carbureter equipped with my improved attachment.

Fig. 3 is a sectional view of a detail showing one form of air valve.

Fig. 4 is an enlarged fragmentary elevational view, partly in section, and illustrating the air supply pipe and its controlling valve.

Fig. 5 is an elevational view of a carbureter equipped with a slightly modified form of my present improvement; and

Fig. 6 is a view similar to Fig. 5 but at right angles thereto, and showing a portion of the carbureter and air valve in section.

Referring more particularly to the drawings, in Fig. 1 there is designated an automobile at 1 which is intended to represent any of the approved makes or types of such vehicles, as my invention is equally applicable to all such cars. At 2 is designated a fuel tank which has the usual perforated cap for closing the filling neck, and which admits atmospheric air to the surface of the fuel in said tank 2 for a purpose to be hereinafter more fully explained.

The fuel in the tank 2 is placed directly in communication with the float chamber 3 of the carbureter 4 by a pipe or other connection 5, one end of which extends down within the fuel tank 2 and into a boss 6 at the bottom thereof with a view to receiving all of the contents of said tank.

As shown more particularly in Fig. 2, the pipe 5 connects with the screen chamber 7 beneath the float chamber 3, and communication between which is under the control of the float valve 8. This latter valve 8 is operated by any suitable device for controlling a constant level of fuel in the chamber 3. This chamber 3 is preferably closed by a removable top 9 secured by fastenings 10, and to which access may be had for purposes of cleaning or adjustment of parts.

100

An extension 11 projects from the carbureter 4, as shown in Fig. 6, and is for the purpose of admitting atmospheric air through a suitable valve and into the aspirating chamber 12. Any conventional nozzle 13 may be located in this aspirating chamber 12 for receiving the fuel from the float chamber 3 and delivering it to the air which is drawn in by the suction 10 of the engine as controlled by the throttle valve 14 above the mixing chamber 15.

This air extension 11 is perforated, as indicated at 16 in Fig. 6, to receive one end of a pipe 17 which extends directly 15 between the float chamber 3 and extension 11, and has its other and upper end secured over a slot 18 in the side wall of the float chamber 3 very close to the removable cover 9. This pipe 17 is provided for the 20 purpose of carrying off the air from the float chamber 3 above the fuel column therein as induced by the suction of the engine cylinders in a manner which will be readily understood. This withdrawal of the 25 air in the float chamber 3 creates a partial vacuum therein such as will tend to suck in fuel through the pipe 5 and the tank 2 when the float valve 8 is raised from its seat.

30 In the form of the invention shown in Figs. 2, 3 and 4, the air extension 11 is closed by a cover plate 19 having a series of openings 20 arranged radially about a central aperture 21; such cover plate 19 being secured over the open end of the extension by any suitable fastening means. Centrally from this cover plate 19 projects a boss 22 having an outer flange 23, which latter confines a spring washer 24. On 40 the boss 22 and held by the spring washer 24 tightly against the front face of the cover plate 19, is rotatably mounted a register valve 25 formed with openings 26 therein of substantially the same size and shape as 45 the above mentioned openings 20; such openings or ports in the cover plate 19 and valve 25 being adapted to register for the purpose of admitting air through the extension 11 and into the aspirating chamber 50 12. By a rotary movement of this valve 25, as more particularly seen in Fig. 2, the series of openings 26 may be moved either partially or wholly out of registry with the openings 20 in the cover plate 19 and 55 thus reduce or completely cut off the air admission.

At low speeds and when starting the engine, it is preferable that very little air be admitted, as a rich mixture is required to 60 secure the initial impetus. On the other hand, at high speeds little fuel and large quantities of air are found to be desirable, and for the purpose of effecting these results the register valve 25 may, with advantage, be connected to and placed under

the operation of the throttle valve 14. This throttle valve 14 is controllable through an operating lever 27 suitably shifted from the steering column. On the opposite end of the stem of the throttle lever 14 is an 70 arm 28, as shown in Fig. 2, having a head 29 provided with lugs 30 and 31. These lugs project in the path of a second and co-operating arm 32, which is connected to the register valve 25 and whereby said valve 75 is rotated. A curved indentation is formed in the arm 32 which is entered by the lug 30 when the arm 28 is swung in one direction whereby to accomplish smooth operation and to yield a loose joint. 80

As more particularly seen in Fig. 4, a recess 34 is provided in the cover plate 19 which communicates with one end of a pipe or other connection 35 having its other and upper end connected to the body of the 85 float chamber 3 near to the removable top 9. This recess 34 is normally closed by the valve 25, but is adapted to be placed in open communication by a port 36 in the edge of said valve, and when in such 90 position atmospheric air is allowed to enter through the connection 35 and into the float chamber 3 to relieve the excessive degree of vacuum created by the high speed of the engine. 95

Referring more particularly to the form of the invention disclosed in Figs. 5 and 6, the air extension 11 of the carbureter is supplied with a valve seat 37 against which is adapted to close a valve 38 which 100 is carried on a stem 39. This stem 39 projects through the hub and an extended bearing 40 of a spider 41, which is secured by a fastening 42 over the end of said extension 11. A coil spring 43, or other means, is provided to close the valve 38 against its seat 37 when the suction in the carbureter is lower than the strength of 105 said spring 43. When the suction exceeds the strength of the spring 43 the valve 38 is drawn away from its seat 37, as shown in Fig. 6, and air is permitted to enter into the aspirating chamber 12 and past the perforation 16 which communicates with the air relief pipe 17. 110

As shown in Fig. 5, the spider 41 is advantageously formed with only two arms which extend in the same diametrical line, and one of which, preferably the upper, is supplied with an air passage 43' which communicates with an annular groove 44 in the hub of said spider. A pipe or other connection 45 has one end fitted through the air extension 11 and in communication with the passage 43'; while its opposite end is attached to the side wall of the float chamber 3 near the removable top 9 in the manner and for a purpose similar to that above described of the similarly functioning pipe 35 as shown in Fig. 2. In the valve stem 39 is a slot 46, the outer 120 125 130

end of which is adapted to be constantly open to the outside air, while the inner end thereof is arranged to be placed in communication with the annular groove 44 only 5 when the valve stem 39 moves inwardly to an extent which is occasioned by a predetermined high speed of the engine.

The following is a brief description of the operation of my improved attachment:

10 When the engine is at rest the parts of that form of my attachment shown in Figs. 2, 3 and 4 will be so positioned that the valve 25 will cut off entirely or almost completely the entrance of air through the ports 26 15 and 20. The central opening 21 will, however, provide for the ingress of sufficient air for a rich admixture, such as is generally required in initially turning over the motor.

As soon as the engine is started and begins to operate of itself, the suction created by the pistons on their down strokes will be communicated to the carbureter, and will be effective to withdraw the air from the top of the float chamber 3 through the pipe 17, 25 and in such manner there will be a partial vacuum formed above the fuel column in said float chamber. As above described, this partial vacuum will induce a flow from the fuel tank 2 when the valve 8 is open, which 30 latter is automatically accomplished to maintain a constant level by the float device. From such float chamber 3 the fuel passes to the aspirating nozzle 13, in the usual manner, where it is picked up by the incoming 35 air and passed on through the mixing chamber 15 and to the engine cylinders as admitted by the throttle valve 14.

As the engine speed increases, due to the opening of the throttle valve 14, the arm 28 40 will in consequence be proportionately swung to the left, as shown in Fig. 2, so that the lug 31 will encounter one side of the companion arm 32 and shift the latter also to the left in a manner which will rotate the 45 valve 25, moving the ports 26 into more complete registry with the ports 20 in the cover plate 19. This action will go on until a full registry is established, which will be the maximum running of the engine. When 50 this maximum running is attained and the complete registry effected, the port 36 in the valve 26 will have been shifted to uncover the recess 34 and permit a free communication of the atmospheric air to the pipe 35 55 and upper part of the float chamber 3.

Thus air from the atmosphere may be admitted to said float chamber and relieve that abnormal degree of vacuum therein which has been induced by the high speed of the 60 engine. The port 36 will, of course, gradually move over the recess 34 and by degrees will admit a greater or less supply of atmospheric air to the float chamber 3 in accordance with the speed at which the engine 65 at any one time is operating; such action re-

sulting in preserving substantially constant the degree of vacuum in the float chamber 3, which is necessary as the float device therein must be initially selected and fitted and set with a view to operating under pre-determined degrees of vacuum.

When the throttle valve 14 is moved in the opposite direction it will also carry the arm 28 to the right, with the lug 30 encountering the opposite edge of the companion 70 arm 32 and shifting the valve 25 in the opposite direction to progressively mask the ports 26 and 20. The port 36 will, in a similar manner, gradually cut down the area of the recess 34 so as to diminish by degrees 80 the amount of atmospheric air admitted through the pipe 35 to the float chamber 3.

With respect to the modification shown in Figs. 5 and 6, the air valve 38 is automatic in action, depending entirely upon the suction within the engine and carbureter, and has no attachment whatsoever to the throttle 85 14. As the suction increases the valve 38 will be drawn farther away from its seat 37 until a predetermined speed has been 90 attained, when the inner end of the slot 46 will arrive at communication with the annular groove 44; thus establishing a communication with the outside atmosphere through the slot 46, annular groove 44, air passage 95 43', and pipe 45 to the upper part of the float chamber 3. The air in this case is admitted for the same purpose of relieving the excessive vacuum in the float chamber, and operates in a like manner to preserve 100 that vacuum constant.

It is obvious that those skilled in the art may vary the details of construction and arrangements of parts without departing from the spirit of my invention, and therefore I do not wish to be limited to such features except as may be required by the 105 claims.

I claim:

1. In a device of the character described, 110 a carbureter having a fuel chamber, a fuel supply in communication with said fuel chamber, means placing said fuel chamber under the influence of the suction produced by the engine whereby to create a partial vacuum above the fuel therein, a connection to said fuel chamber for admitting air thereto, and a valve both for regulating the supply of air to the carbureter and for controlling the admission of air to the fuel chamber to relieve the excessive vacuum, substantially as described.

2. In a device of the character described, 115 a carbureter having a fuel chamber, a fuel supply in communication with said fuel chamber, means placing said fuel chamber under the influence of the suction produced by the engine whereby to create a partial vacuum above the fuel therein, a connection to said fuel chamber for admitting air 120 125 130

thereto, and an air-supply valve for said carbureter, said valve carrying a port into and out of registry with said connection for admitting fluid to said fuel chamber when an 5 excessive vacuum is produced, substantially as described.

3. A system of the character described including a carbureter having the usual float chamber, a fuel tank, a connection directly 10 placing said fuel tank in communication with said float chamber, an extension on said carbureter forming an air intake, a valve controlling the admission of air through said air intake, a pipe connected at one end 15 near the top of said float chamber and at its opposite end to said air intake, a second pipe having one end in communication with the top of said float chamber and the opposite end attached to said carbureter extension but normally closed by said air valve, 20

said valve adapted to open to a predetermined degree and place said last named pipe in communication with the atmospheric air, substantially as described.

4. An attachment of the character described including a carbureter having a float chamber and an air intake extension, a removable top for said float chamber, a pipe connected directly between said air intake extension and the body of said float chamber near the removable top, a second pipe connected at one end to the body of the float chamber near said removable top and having its other end secured to said extension, and means for placing said last named pipe in communication with the external atmosphere, substantially as described. 25 30 35

In testimony whereof, I affix my signature.

FREDERICK L. McCULLOCH.
